UNITED STATES PATENT OFFICE.

THOMAS S. STEWART, OF SALTSBURG, PENNSYLVANIA.

END-GATE FOR DUMPING-WAGONS.

SPECIFICATION forming part of Letters Patent No. 315,969, dated April 14, 1885.

Application filed October 11, 1884. (No model.)

To all whom it may concern:

Be it known that I, THOMAS S. STEWART, a citizen of the United States, residing at Saltsburg, in the county of Indiana and State of Pennsylvania, have invented certain new and useful Improvements in End-Gates for Dumping-Wagons; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a side view of a cart, showing my improved end-gate; and Figs. 2 and 3 are side views of the end-gate detached from the cart. Fig. 4 is a view of the end-gate from the rear.

20 This invention, which is an improvement on the patent granted to me on the 11th day of March, 1884, and numbered 295,072, relates to improvements in dumping-wagons; and it consists in the construction and novel arrangement of parts hereinafter described, and pointed out in the appended claims.

25 The object of the invention is to provide means whereby the end-gate may be turned onto the backward extensions of the body-rails in line with the floor of the wagon-body.

30 In the accompanying drawings, A A represent the side bars, fixed to and standing backward from the rear ends of the shaft a a.

35 B B are standards rising from the ends of the side bars, and having the end-gate hinged to their ends at C C.

40 D D are brace-rods running near the upper ends of the standards forward and downward to the side bars.

45 E E are actuating-rods connected to the side straps of the end-gate by the eyebolts or eyes e e, and having their front ends pivoted upon the sides of the wagon-body e'.

When the wagon-body is thrown down, the 45 standards maintain their positions, and the motion of the body, by means of the rods E, thrusts the lower edge of the end-gate backward and upward, and as the end-gate does not change position, but turns only, the body

50 descends below it and the rear end of the former becomes uncovered.

The end-gate is constructed in the following manner:

F F are metal straps on which the eyes e e are cast. The lower end of each strap F is 55 bent backward and slightly downward, and forms the middle part of the hinge-joint f, as shown.

G G is a metallic head-piece formed on the upper end of the strap F and projecting backward therefrom. g g is a latch moving in a recess on the head-piece, and controlled by the spring g'. g' is a detent to prevent the spring driving the latch too far out of the head-piece. The hinge-bearings c are formed on the head- 65 pieces.

H H is an iron strap, the lower end of which forms the outer part of the hinge-joint f, and the upper part of which extends over the covering-board. The hinge f is completed in 70 the usual manner by inserting a pin, f'.

I I is a board fixed by its ends to the straps G, lying between said straps and the straps F, and covering the discharge end of the wagon. i i is a detent-notch made in the metal-covered 75 corner of the upper edge of the board I. The points of the latches g g engage in said notches and keep the board I in place. When the latches are raised out of the notches, the said board may be turned down on the body-rails, 80 and the discharge end of the wagon will be uncovered.

The advantage of this construction is that the loading of the wagon will be much facilitated, and in loading with heavy packages or 85 bodies the same will not have to be lifted over the sides of the wagon or the end-gate.

Having thus described my invention, what I claim as new, and desire to secure by Letters Patent, is—

1. In a dumping-wagon, the combination, with the body, shafts, side bars, A, secured to the rear ends of the shafts, standards B, fixed to the rear ends of the side bars, and actuating-rods E, of the end-gate C, hinged to the upper 95 ends of the standards at c c, and composed of the straps F and H, hinges f, head-pieces G, board I, and suitable devices to connect and disconnect said head-pieces and board at will, substantially as specified.

2. In an end-gate for a dumping-wagon, the combination of the straps F, head-pieces G,

and latch g , provided with detents g^2 and controlled by the spring g' , with the hinges f , straps H , board I , and notches i i , adapted to receive and hold the point of the latches, substantially as specified.

3. In a dumping-wagon, an end-gate having side straps forming part of said gate, to the lower end of which straps the end-board is hinged and to the upper end of which straps it is connected by automatic catches, substantially as specified.

4. In a dumping-wagon, an end-gate com-

posed of vertical end straps carrying head-blocks on their upper ends and hinged at the lower ends to vertical straps, to which the end or covering board is fixed, and suitable devices to automatically engage the head-pieces to the end-board, substantially as specified. 15

In testimony whereof I affix my signature in presence of two witnesses.

THOS. S. STEWART.
